CLAIM

The ornamental design for a tire for autocycle, as shown and described.

DESCRIPTION

FIG. 1 is a front elevation view of a tire for autocycle showing our new design;

FIG. 2 is a side elevation view thereof, the opposite side being substantially a mirror image of that shown;

FIG. 3 is a perspective view thereof, it being understood that the tread pattern is repeated uniformly throughout the circumference of the tire; and

FIG. 4 is an enlarged cross-sectional view thereof taken along line A—A in FIG. 1.
